UNITED STATES PATENT OFFICE.

HARRISON BUCKLIN, OF ROCHESTER, NEW YORK, ASSIGNOR, BY MESNE ASSIGNMENTS,
TO SAMUEL D. YOUNG, TRUSTEE, OF GRAND RAPIDS, MICHIGAN.

GOODS-DISPLAY DEVICE.

1,115,498.

Specification of Letters Patent.

Patented Nov. 3, 1914.

Application filed July 21, 1911. Serial No. 639,750.

To all whom it may concern:

Be it known that I, HARRISON BUCKLIN, of Rochester, in the county of Monroe and State of New York, have invented certain new and useful Improvements in Goods-Display Devices; and I do hereby declare the following to be a full, clear, and exact description of the same, reference being had to the accompanying drawings, forming a part 10 of the specification, and to the reference-numerals marked thereon.

My present invention relates to goods display devices and has for its object to provide in connection with a rotatable rack or holder, on which the goods may be supported, mechanism for causing the rack or holder to assume a definite predetermined position in reference to the base or support on which it may be mounted each time the rack or 20 holder is caused to be turned a partial revolution so that it is adjusted out of its normal position.

To these and other ends the invention consists in certain improvements and combinations of parts, all as will be hereinafter more fully described, the novel features being pointed out in the claims at the end of the specification.

In the drawings: Figure 1 is a top plan view illustrating a type of goods display apparatus arranged within a show case to which devices embodying my invention may be applied; Fig. 2 is a detail view in side elevation, illustrating the mounting of the 35 rack or support upon the carriage, used with the arrangement of parts shown in Fig. 1. Fig. 3 is an enlarged side elevation showing a plurality of racks or holders mounted upon a stationary column or support; Fig. 40 4 is an enlarged cross sectional view on the line 4^x—4^x of Fig. 2, showing the detail arrangement of parts adopted as one embodiment of my invention which may be employed when the rack or holder rotates upon 45 the support; Fig. 5 is a similar view showing the arrangement of the same parts inverted, which may be employed when the rack is rigidly connected to the support and the latter rotates on its supporting base; 50 Fig. 6 is a cross sectional view taken on the line 6^x—6^x of Fig. 4; Fig. 7 is a detail perspective view of the cam member; Figs. 8 and 9 are detail cross sectional views showing structures embodying further modifications of my invention, and Fig. 10 is a sec-

tional view taken on the line 10^x—10^x of Fig. 9.

Similar reference numerals in the several figures indicate similar parts.

In illustrating my invention I have shown 60 a type of display apparatus adapted particularly for use in exhibiting clothing, comprising a rack composed of the parallel bars 1, 1, upon which the various articles or garments are suspended by suitable garment 65 hangers, said rack being mounted upon a frame 2 mounted on the upper end of a column or support 3. The latter in apparatus of this type is held in vertical position by mounting it upon a carriage 4, which is employed when the device as a whole is inclosed in a wardrobe or cabinet, as shown in Fig. 1, the carriage then being preferably guided on rails 5 to permit the rack to be drawn forwardly to facilitate access to the goods when 70 the doors of the cabinet are open. The invention, however, is applicable to display racks adapted for other purposes than those mentioned, and the standard or column 3 may be held in a vertical position by any 75 suitable form of base, such as that indicated by 6 in Fig. 3.

In most instances it is preferable to construct display racks rectangular in outline, 80 making them of greater length than width, 85 as this shape not only adapts the racks or supports for general store use, but also lends itself conveniently to the supporting of a large number of goods, since they can be made to occupy a minimum amount of floor 90 space for a given holding capacity, while the goods on the various parts of the rack may be readily accessible when the device is revolved. Irrespective of the character of the articles which may be supported upon 95 the rack, the desideratum to be obtained in the use of any rotary display device is to maintain it in a definite predetermined position, except when the operator is rotating it, so that the rack may not project into the 100 aisle or passageway of the store, and under normal conditions will be parallel to or in alinement with other similar racks or other adjacent articles of furniture with regard to which it may be desired to have said racks 105 assume a particular relationship.

As a means of accomplishing this object, I have shown as one embodiment of my invention an arrangement of parts for automatically restoring the rack or goods holder, 110

previously described, to its normal position in parallelism with the open front of the inclosing cabinet or wardrobe, whenever it has been rotated a partial revolution, irrespective of which of the two sides of said rack is outermost, or the direction in which it may have been rotated. In carrying out my invention the standard 3 may be held rigid and non-rotatable as in Figs. 2, 3 and 4, the 10 rack being revoluble thereon, or the latter may be rigidly connected to the standard and said standard journaled in its base, as shown in Fig. 5. So far as the broad feature of the invention is concerned, it is immaterial 15 whether the column or its attached rack constitutes a movable element revolving in the stationary base, or whether the column is rigid and constitutes with the base a stationary element in respect to which the rack is rotatable, and becomes the movable element 20 of the structure. In conjunction with these two parts, which may be termed broadly stationary and revoluble elements, I employ a cam on one part and on the other 25 a bearing member or members coöperating therewith, and so disposed that the weight of the goods support or rack when displaced out of its normal position, will cause the cam and its bearing members to coact and restore 30 the movable element to its proper position in respect to the stationary element.

As one means of carrying out my invention, I have shown in Fig. 4, the column 3, which is stationary and is provided at its 35 upper end with a sleeve 7 which may be adjusted thereon at the desired elevation and secured by set screws or other fastening devices 8. The frame 2 of the rack or holder is provided with a top portion 9 which surrounds the standard and a bottom 10 provided with a larger recess receiving the sleeve. The frame 2 is supported upon an annular row of anti-friction ball bearings 11 arranged between its top 9 and the upper 45 end of the sleeve. The sleeve near its lower end is provided with an enlarged collar 12 having at opposite sides apertures in which are arranged rollers 13 and 14 constituting bearing members with which the cam member 15 coöperates, the latter in the present 50 instance, resting upon said rollers, and being provided with ears 16 guided between lugs or flanges 17 on the inner side of the frame 2 which permit the cam member to move vertically relatively to the frame. The cam member surrounds the sleeve and is provided upon its lower surface with a plurality of cam surfaces, two in the present 55 instance being shown and indicated by 18 and 19, which are preferably of equal extent their high points 20 and 21 being diametrically opposed. The low points or bases of the cams are provided with slight 60 depressions 22 and 23, for a purpose which 65 will further be described.

In many instances the racks with the goods thereon have an aggregate weight of several hundred pounds, and as it is only necessary to utilize a portion of this weight and thus permit the rack to be rotated with 70 less effort on the part of the operator, I have provided means for adjusting the effective effort exerted by the weight of the parts to restore them to normal position. This is accomplished by providing a longitudinal movement of the cam 15 relatively to the frame 2 and arranging tensioning devices, such as a plurality of springs 24 between said cam and the frame 2, which may be adjusted by set screws 25. 80

In Fig. 5 I have shown a modification of the parts described above, in which the frame 2^a is rigidly connected to the standard or column 3^a, rotatable on the base 4^a. The parts shown in this figure are a duplication 85 of the ones illustrated in Fig. 4, the parts therein shown being merely inverted.

As another means of carrying out my invention, I have shown in Fig. 8 the column 30 journaled at its lower end in the base 31 90 and supported by a recessed collar 32, between which and the upper face of the base is arranged a circular row of bearing balls 33. The cam member indicated by 34 surrounds the column within the collar and is 95 provided upon its lower surface with two cam surfaces coöperating with the rollers 35 and 36 journaled in the base 31 at opposite sides of the column. The proportion of the total weight of the rack which it is desired 100 to apply to the cam member 34 is determined by the compression given the springs 37 by adjustment of the set screws 38, the cam member in this instance being permitted to move longitudinally on the column by means 105 of a slot and pin connection, as indicated by 39.

Another modification of the invention is illustrated in Figs. 9 and 10, in which the cam member 40 is attached rigidly to the 110 standard or column 300, and rests upon the rollers 41 and 42 on the stationary element or base 43 in which the lower end of the standard is journaled. A supplemental bearing is provided to carry the major portion 115 of the weight of the parts, consisting of the balls 44 located beneath the underside of the cam member and resting upon a collar 45 loosely surrounding the column 300. Projecting laterally from the bottom of the collar and beneath the bottom of the cam member 40 are ears 46 beneath which are coil springs 47 which may be adjusted by set screws 48 to determine the proportion of the weight which is to be carried by the 120 bearing and cam member respectively.

In the structures illustrated in Figs. 8 and 9, the parts are shown arranged in the manner employed when the standard rotates with the rack and is journaled in the base 130

or support, and in Fig. 3 I have shown the adaptability of these two forms of the apparatus to a structure in which the support or column is immovable, this illustration being also used to convey the idea of mounting upon a single column a plurality of racks or holders for goods. In Fig. 3 the racks shown are independently revoluble, the lower one indicated by A comprises the stationary element 310 corresponding to the base 31 and the movable member or head 320, which is the same as the collar 32, with the exception that the rack frame 200 is attached directly thereto. When a second rack is employed the column is extended upwardly the desired distance, and at the proper elevation the second rack D is located thereon. The parts supporting the second rack may be a duplication of those last mentioned, but in order to show the adaptability of the mechanism disclosed in Fig. 9, I have again illustrated the latter, this mechanism in Fig. 3 embodying a stationary element 430, the same as the base 43, which is fixed to the standard and the member 400 (corresponding to the cam 40) to which the rack frame 201 is connected.

In operation the weight of the rack or rotatable element acting to move it downwardly exerts a constant force between the cam member and its coöperating bearing members whenever the rack is rotated or adjusted out of its normal position, and this force, it will be understood, may be adjusted or regulated by the tension imparted to the springs. The inclined faces of the cam members move along their respective bearings or rollers until their lowest points are directly above the axes of said rollers. When the cam members are in this position the arms of the rack or goods supporting devices are in the position previously determined to be the desired normal position of rest where they are held by the slight depressions 22 and 23. The latter are comparatively shallow and their depth may be varied according to requirement, their function being to require the operator to exert a slight force at the commencement of the rotary movement of the rack, thus normally holding the rack against accidental displacement. These depressions also serve to assist in bringing a heavily loaded rack to a position of rest and limit its oscillatory movement, permitting the cam surfaces to be made shallow or with but a slight deflection.

Devices embodying my invention, when employed in connection with garment supporting racks which are adapted to be enclosed in a wardrobe or cabinet, as shown in Fig. 1, possess a particular advantage in that the rack is automatically "straightened up" or adjusted parallel to the front of the case. In this position the rack may be

moved rearwardly into the cabinet, the carriage on which it is mounted traveling along the tracks on the bottom of the case. The same force which acts to turn the rack automatically into its normal position serves to hold it in this position, the rack, however, being at all times rotatable when the resistance of the load acting through the cam surfaces is overcome. This resistance to the rotary movement of the rack which is substantially uniform at all points of rotation, may be adjusted as circumstances require, and contributes an advantageous feature to a wardrobe apparatus such as illustrated, since the carriage being free to travel on its ways, may be drawn forwardly or impelled rearwardly by the operator grasping any part of the rack.

While I have illustrated and described my invention as embodied in a garment display apparatus, and for this reason constructed of parts necessarily large and heavy, it will be understood that in its broadest aspect it is equally applicable to goods display devices of other types and for other uses, as an example of which small display stands for holding neckties, handkerchiefs or similar articles may be mentioned, in which event the parts may be made of lighter construction adapting them to be mounted upon show cases or store counters.

I claim as my invention:

1. In a display device, the combination of a cabinet, a rotatable goods support movable to and from a position within said cabinet, a sustaining means for said goods support, a cam member and a coöperating bearing member, one connected to the rotatable goods support and the other to the sustaining means, and one of said members being yieldingly mounted for vertical movement independent of vertical movement of the part to which it is connected and acting through such independent vertical movement to cause the goods support to assume a predetermined position when turned from said position and released.

2. In a display device, the combination of a case or cabinet, a rotatable rack and a support for said rack movable to and from a position within the case or cabinet, a cam member and a bearing member relatively movable in a vertical direction for returning the rack to a predetermined position when moved from said position and released, and yielding means acting on one of said members permitting it to move vertically relatively to the other member as the rack is turned in a single horizontal plane.

3. The combination with a horizontally revoluble goods support and a base on which it is mounted, of a cam member having two inclined cam faces, and bearing members coöperating with said faces, the

cam member being yieldingly mounted on the goods support to permit it to rise independent of rising movement of the goods support and the bearing members arranged 5 on the base.

4. The combination with a horizontally revoluble goods support and a base on which it is mounted, of a cam member connected to the goods support to rotate therewith but movable vertically independent 10 thereof and having an inclined cam surface on its lower side, a bearing member on the base coöperating with said cam surface and serving to displace the cam member vertically independent of the goods support during 15 a partial rotation of the goods support, said cam and bearing member coöperating to cause the support when at rest to normally assume a predetermined position.

20 5. The combination with a horizontally revoluble goods support and a standard on which it is mounted, of coöperating cam and bearing members mounted one on the standard and the other on the goods support, a 25 thrust bearing for the latter, and means for varying the proportion of the weight of said support carried by the thrust bearing and by the cam and its bearing members respectively.

30 6. In a goods display apparatus, the combination with a standard and a goods display rack rotatable freely in a horizontal plane and supported on the standard, of a cam member on one of said parts having 35 cam surfaces, and bearing members on the other of said parts coöperating with said surfaces to automatically restore the rack to its normal position when it has been revolved out of such position, and means permitting relative vertical movement of said cam member and bearing member independent 40 of relative vertical movement of the rack and standard.

7. In a display apparatus, the combination 45 with a base, a rack revoluble relatively thereto and a thrust bearing between said parts sustaining the weight of the rack, of a cam having a plurality of cam faces and coöperating bearing members engaging therewith, said cam and members being arranged 50 relatively to each other on the base and rack and coacting to automatically adjust the rack into a predetermined position, and adjustable means arranged between the rack 55 and cam for varying the amount of pressure exerted between the cam and its bearing members.

8. In a display device, the combination of 60 a rotatable rack for displaying goods, a support for said rack, a cam member on one of said parts and a bearing member on the other part, and a spring acting to force said members together and permitting vertical movement of said members independ-

ent of relative vertical movement of the 55 rack and its support.

9. In a goods display apparatus, the combination with a vertical column and bearing members projecting therefrom, of a goods display rack comprising a frame, a cam member having inclined faces resting on the bearing member and yieldingly adjustable tension devices between the cam member and the frame.

10. In a goods display apparatus, the 75 combination with a vertical column, a bearing thereon and a horizontally rotatable goods supporting frame journaled on the bearing, of bearing members on the column, a cam member having inclined faces resting 80 on said members and means between the frame and cam member for adjusting the pressure exerted by the cam member on its bearing members.

11. In a goods display apparatus, the 85 combination with a column, a sleeve thereon having bearing members and a goods supporting frame journaled on the column and resting on the sleeve, of a cam member having inclined surfaces resting on the bearing 90 members and springs between the cam member and frame and means for adjusting them to vary the pressure between the cam faces and their bearing members.

12. In a goods display apparatus, the 95 combination with a column, a sleeve thereon having bearing members and a cam member having inclined faces coöperating with said bearing members, of a goods support revoluble on the column and yielding connections 100 between said support and cam member sustaining part of the weight of said support.

13. In a goods display apparatus, the combination with a goods supporting frame 105 having a central aperture, an apertured cam member movable relatively thereto and compression springs between it and the frame, of a standard extending through the cam into the frame, a bearing on the standard for supporting the frame and a supplemental bearing on said standard coöperating 110 with the cam member.

14. In a goods display apparatus, the combination with a column, a sleeve adjustable longitudinally thereon and a goods supporting frame surrounding the column and journaled on the sleeve, of a cam member surrounding the latter having inclined faces and movable on the frame longitudinally of the sleeve, bearing members on the latter coöperating with the inclined faces of said cam member and means arranged between the frame and cam member for yieldingly supporting a portion of the weight of said frame on the cam member.

15. In a goods display apparatus, the combination with a stationary base and a

horizontally revoluble goods supporting frame journaled thereon, of rollers on the base, a cam member having inclined faces co-operating with said rollers and yielding 5 tension devices between the frame and cam member adapted to support a portion of the weight of the frame on said cam member.

16. In a display device, the combination 10 of a cabinet, a carriage movable to and from a position within the cabinet, a rotatable rack movable with the carriage, a

cam connected to the rack to rotate therewith and having vertical movement independent of vertical movement of the rack, and a bearing coacting with said cam to 15 cause the rack to automatically assume a position parallel with the case when partially rotated and released.
